UNITED STATES PATENT OFFICE

162,864

TOWEL RACK

Herman Nielsen, Tuckahoe, N. Y., and Gilbert Forrester, West Brooksville, Maine

Application January 12, 1950, Serial No. 7,187

Term of patent 7 years

(Cl. D33—16)

To all whom it may concern:

Be it known that we, Herman Nielsen and Gilbert Forrester, both citizens of the United States, residing, respectively, at Tuckahoe, State of New York, and West Brooksville, State of Maine, have jointly invented a new, original and ornamental Design for a Towel Rack, of which the following is a specification, reference being had to the accompanying drawing forming part thereof, and in which:

Fig. 1 is a front perspective view of a towel rack showing our new design, and

Fig. 2 is a side elevational view of the same. The rear of the towel rack is plain.

We claim:

The ornament Design for a towel rack, as shown and described.

HERMAN NIELSEN.

GILBERT FORRESTER.
